[57] **CLAIM**

The ornamental design for a computer memory disk cartridge, as shown and described.

DESCRIPTION

FIG. 1 is a perspective view of a computer memory disk cartridge;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; and,

FIG. 7 is an opposite side elevational view thereof.
